VANITY CASE

Original Filed July 25, 1928

INVENTO

David H. Zell
BY C. P. Goefel,
his ATTORNEY

UNITED STATES PATENT OFFICE

DAVID H. ZELL, OF BROOKLYN, NEW YORK

VANITY CASE

Original application filed July 25, 1928, Serial No. 295,294. Divided and this application filed January 22, 1929. Serial No. 334,311.

This invention relates to vanity cases, and has for its general object and purpose to provide a device of this character which is novel and attractive in form and appearance, 5 the several parts of which can be inexpensively fabricated in the form of simple sheet metal stampings, and which is also of great convenience and serviceability in practical use.

10 The subject matter of the present application constitutes a division of my pending application Serial No. 295,294, filed July 25, 1928, and in one practical embodiment of the device I propose to construct the same 15 in the form of a miniature kodak or camera of the folding type. To this end, the body of the case may be conveniently produced from a sheet metal stamping having a wall constituting the bottom or rear side of the 20 case and the opposite ends of which are formed into return bends providing narrow transversely extending compartments at the opposite ends of the case body and said body wall of the case having edge flanges closing 25 the opposite ends of said compartments. The opening at the front side of the case between the confronting end edges of said body wall is adapted to be closed by a hingedly mounted cover or closure member. One of the end 30 compartments above referred to, I utilize as a housing for a suitable latch means for this cover or closure while the other of said end compartments receives and houses a removable lipstick or other cosmetic.

35 It is also an important object of my invention to provide a supporting frame for the hinged door or closure arranged within the case body and rigidly secured to said bottom or rear wall thereof, together with an 40 ornamental flexible covering material for the body wall consisting of a single sheet engaged and securely held at its ends by parts of said frame, and means secured to the side flanges of the case body and also cooperat- 45 ing with said covering material to prevent

lateral shifting movement thereof relative to the case.

The invention further contemplates the provision of simple and reliable means for removably holding cosmetic containing pans 50 within said frame and preventing the accidental release or displacement thereof in the use of the device.

With the above and other objects in view, the invention consists in the improved vanity case and in the form, construction and relative arrangement of its several parts, as will be hereinafter more fully described, illustrated in the accompanying drawings, and subsequently incorporated in the sub- 60 joined claims.

In the drawings, wherein I have shown one simple and practical embodiment of the invention, and in which similar reference characters designate corresponding parts 65 throughout the several views,—

Figure 1 is a perspective view of my improved vanity case, showing the same closed;

Fig. 2 is a plan view of the case on an enlarged scale showing the same open, and 70 parts of the case including the hinged cover or closure means shown in section, and

Fig. 3 is a longitudinal sectional view taken substantially on the line 3—3 of Fig. 2.

Referring in detail to the drawing, it will 75 first be observed that the body of the case is comparatively flat or shallow and the opposite ends thereof are rounded or convex so that in general outline form the case will closely simulate in miniature a folding camera or kodak. As shown, the case body is produced from a sheet metal stamping which includes the bottom or rear wall 35 of the case having the return bends 36 at the opposite ends thereof and longitudinally extending flanges 37 at its opposite edges disposed in a plane at right angles to the wall 35, and closing the opposite ends of the narrow transversely extending chambers or compartments formed by the return bends 36. The end 80

portions of these bends 36 extend in parallel relation to the wall 35 and form the front side of the case body, the space between the confronting end edges thereof and between the flanges 37 defining the open front side of the case which is adapted to be closed by means of a hinged cover or closure member to be later referred to.

Within this case body a rectangular metal frame 38, preferably of sheet brass, is arranged, the walls of this frame being of angular cross section and the base flanges thereof detachably secured to the bottom or rear wall 35 of the case body, as for instance, by means of the tongues 39 struck from said wall and clinched upon the frame flanges.

The external surfaces of the bottom or rear wall 35 and the inwardly turned ends 36 thereof are preferably covered by a sheet of ornamental flexible material indicated at 40, such as imitation leather or the like, and as a simple and reliable means for securely holding this flexible sheet against longitudinal shifting on the body walls of the case, I turn the end edges of said sheet inwardly over the end edges of the end portions 36 of the body wall and securely clamp the same thereon by means of the out-turned flanges 38' on the opposite ends of the frame 38.

For the purpose of holding this ornamental flexible sheet 40 against lateral shifting on the body walls of the case and also for purposes of additional ornamentation, I provide the elongated edge plates 41 having narrow laterally projecting flanges 41'. These plates 40 are adapted to be fitted closely against the outer side faces of the flanges 37 of the case body, with the flanges 41' on said plates having close frictional engagement upon the body walls 35 and 36 and extending over the edges thereof in the plane of said covering sheet 40. Any suitable means may be provided for rigidly securing the edge plates 41 in their applied positions. For this purpose, in the illustrated embodiment of the invention, I have shown each of the flanges 37 of the case body in spaced relation to its opposite ends as having the inwardly struck portions 42 separated at one of their ends from said flanges to provide the openings at 42'.

To the inner face of each edge plate 41 in spaced relation to its opposite ends the longitudinally disposed metal strips 43 are secured and are offset at one of their ends to provide the tongues 44. These tongues are adapted for engagement through the openings 42' in the flanges 37 as the case body and the plates 41 are longitudinally shifted relative to each other whereby said plates may be securely interlocked with the body flanges 37.

Within the narrow transverse compartment formed between one of the inwardly turned ends 36 of the body wall and one end

of the frame 38, a transversely positioned guide tube 46 is secured between the flanges 37 and is adapted to receive the lipstick holder 47, said holder consisting of the usual tube having a slot 48 in one side wall for the outwardly projecting pin 49 on the end cap of the lipstick whereby the lipstick may be adjusted and projected beyond one end of the holder. One side wall of the guide tube 46 is also provided with a similar slot 50 to receive the pin 49 when the lipstick holder is inserted within the housing, one end of said holder being provided with an ornamental swiveled finger piece indicated at 51 for the purpose of conveniently inserting the lipstick and its holder within the guide tube or withdrawing the same therefrom. When the lipstick is not in use, it will be seen that it is completely housed within the end compartment of the case body externally of the frame 38, and the closed end of the holder 47, is flush with the outer surface of the edge plate 41.

Between the opposite longitudinal flanges 37 of the case body and within one end of the frame 38 a door or closure for the open side of the case indicated at 52 is mounted on the spring hinge 53. While this cover or closure might be of any suitable construction, it preferably consists of a rectangular ornamental sheet metal frame to one side of which a mirror indicated at 54 is suitably attached. Within the marginal frame, a sheet of ornamental covering material similar to that covering the case body is secured to the back of the mirror. At its free end the door frame is provided with an angularly projected curved flange 55 adapted to fit within the opposite end of the frame 38, said flange being formed with a latch member receiving opening 56 therein.

Between the latter end of the frame 38 and the other inwardly curved end 36 of the body wall of the case, latch means for said door is housed and concealed. This latch means may assume various structural forms, but as herein shown, it consists of a yieldable spring metal plate 57 suitably fixed at one of its ends to the frame 38 and having its other or free end angularly bent or curved as shown at 58. One end edge of this latch plate is provided with an angularly projecting lug or finger 59 extending through a suitable opening provided in the end wall of the frame 38. In a suitable guide 60 projecting inwardly from one end of one of the edge plates 41, a pin or button 61 is slidably mounted, the inner end of said button having a head 62 bearing on the end 58 of the latch member 57.

Within the frame 38, intermediate of its ends a transverse bar 63 is arranged, and the outer edge of this bar is rounded or cylindrically formed as at 64. Said bar terminates in suitable pivot studs 65 which are loosely

mounted on the opposite side walls of the frame 38. Between this bar and the opposite ends of the frame 38 the rouge and powder trays or receptacles indicated at 66 are adapted to be arranged. The pivoted bar 63 admits of one of these trays being readily positioned between said bar and the spring hinge 53 of the cover or closure 52. In order to position the other tray or holder 66 between said bar and the opposite end of the frame 38, it is necessary to push the pin or button 61 inwardly, thereby withdrawing the latch finger 59 through the opening in the end wall of the frame so that one end wall of the holder 66 may be positioned beneath the enlarged cylindrical edge 64 of the bar 63 while the other end of the holder abuts closely against the end wall of the frame 38. Upon the releasing the pressure on the pin 61, the latch finger 59 returns to its normal position over the latter end wall of the holder as shown in Fig. 3 of the drawings. Thus, by means of this latch finger and the enlarged or cylindrical edge 64 of the bar 63 the two trays or holders will be securely retained within the case when the door or cover 52 is open and regardless of the angle at which the case may be held in the hand.

When the door 52 is moved to its closed position, the curved flange 55 thereof forces the latch finger 59 outwardly with respect to the end wall of the frame 38 until the opening 56 in said flange is in line with the latch finger whereupon the spring plate 57 projects the latch finger into said opening to thus securely retain the door in its closed position against the action of the spring hinge 53.

As will be noted from reference to Fig. 1 of the drawings, when the door or closure is in its closed position, the outer or exposed surfaces of the door frame, the covering material 52 on the door, the outer surface of the covering material 40 on the case body and the surfaces of the flanges 38' on the frame 38 and flanges 41' on the edge plates 41 at the front side of the case, are all disposed in a common plane so that the front side of the case throughout the length and width thereof will be without projections or protuberances of any kind. Also the bright metal parts of the edge plates 41 and the frame of the door 42, in contrast with the ornamental covering sheets on the door and the case body give to the case a very novel and attractive appearance.

When the ornamental covering material 40 on the body wall of the case becomes soiled or damaged, it may be readily detached by simply disconnecting the frame 38 in which the hinged door or closure is mounted, from the body of the case. A new covering sheet of the same or different design may then be applied and the frame 38 re-attached to the case body. Also, since the facing sheet of ornamental material on the door 52 is at-

tached merely by adhesive, this sheet likewise can be removed and a new facing sheet substituted therefor. The ornamental metal plates 41 when damaged or dull can be easily detached and replaced by new ones.

From the foregoing description considered in connection with the accompanying drawings, the construction and several advantages of my improved vanity case will be clearly and fully understood. It will be seen that the several parts are of simple mechanical form and can be rapidly and inexpensively fabricated from sheet metal so that such a case may be profitably manufactured and sold at relatively small cost.

Also, notwithstanding the small dimensions of the case, it has a comparatively large capacity in view of the fact that the lipstick and latch means for the door or closure are housed within the small end compartments of the case body, thus permitting of the utilization of the entire remaining internal area of the case for the reception of the powder and rouge trays which can be of comparatively large size. It will be understood however, that the essential and novel characteristic of my present invention resides in the form and construction of the case body and the means for securing the ornamental flexible sheet metal on the outer surfaces thereof. The construction and arrangement of the interior frame 38 together with the retaining means for the trays therein and the mounting and construction of the door or closure might be variously modified while retaining the essential characteristics of my invention. Therefore, it is to be understood that in the practical development of the device, the privilege is reserved of resorting to various structural alternatives for the various features of the invention as herein described, and as may be fairly incorporated within the spirit and scope of the invention as claimed.

I claim:

1. A case having a body consisting of a sheet metal plate forming the rear side of the case and having its end portions inwardly directed towards each other to form the opposite ends and front side of the case body, a sheet of flexible material covering the outer surfaces of said body plate, and means detachably secured to the case body to removably secure said covering material against longitudinal or lateral movement relative thereto.

2. A case having a body consisting of a sheet metal plate forming the rear side of the case and having its end portions inwardly directed towards each other to form the opposite ends and front side of the case body, a sheet of flexible material covering the outer surfaces of said body plate, means securing the ends of the covering sheet to the ends of the body plate, and means on the opposite lateral edges of the case body having parts positioned in the plane of the covering sheet

- to prevent lateral shifting movement thereof relative to the case.
3. A case having a body consisting of a sheet metal plate forming the rear side of the case and having its end portions inwardly directed towards each other to form the opposite ends and front side of the case body, a sheet of flexible material covering the outer surfaces of said body plate, and means detachably secured within the case and having parts engaging the opposite ends of said covering sheet to removably secure the latter upon the body of the case.
4. A case having a body consisting of a sheet metal plate forming the rear side of the case and having its end portions inwardly directed towards each other to form the opposite ends and front side of the case body, a sheet of flexible material covering the outer surfaces of said body plate, means detachably secured within the case and having parts engaging the opposite ends of said covering sheet to removably secure the latter upon the body of the case, and means secured on the opposite lateral edges of the case body and having parts positioned in the plane of the covering sheet to prevent lateral shifting movement thereof relative to the case.
5. A case having a body consisting of a sheet metal plate forming the rear side of the case and having its end portions inwardly directed towards each other to form the opposite ends and front side of the case body, a sheet of flexible material covering the outer surfaces of said body plate and secured at its ends thereto, and longitudinally extending plates secured to the opposite lateral edges of the case body and having marginal flanges extending inwardly over the body plate in the plane of said covering sheet to prevent lateral shifting movement of said sheet relative to the case.
6. A case having a body consisting of a sheet metal plate forming the rear side of the case and having its end portions inwardly directed towards each other to form the opposite ends and front side of the case body, a sheet of flexible material covering the outer surfaces of said body plate, a hinged closure for the open front side of the case between the end edges of the body plate, a supporting frame for said closure, said frame having parts bearing upon the end edges of the covering sheet to removably secure said sheet upon the case body, and means for detachably securing said frame within the case.
7. A case having a body consisting of a sheet metal plate forming the rear side of the case and having its end portions inwardly directed towards each other to form the opposite ends and front side of the case body, a sheet of flexible material covering the outer surfaces of said body plate, a hinged closure for the open front side of the case between the end edges of the body plate, a supporting frame for said closure, said frame having parts bearing upon the end edges of the covering sheet to removably secure said sheet upon the case body, and means for detachably securing said frame within the case.
8. A case having a body consisting of a sheet metal plate forming the rear side of the case and having inwardly directed end portions to form the opposite ends and front side of the case and longitudinally extending flanges forming the opposite lateral edges of the case body, a frame secured within the case and having end walls cooperating with the ends of the body plate of the case to provide end compartments exteriorly of said frame, and a hinged door or closure for the front side of the case supported in said frame.
9. A case having a body consisting of a sheet metal plate forming the rear side of the case and having inwardly directed end portions to form the opposite ends and front side of the case and longitudinally extending flanges forming the opposite lateral edges of the case body, a frame secured within the case and having end walls cooperating with the ends of the body plate of the case to provide end compartments exteriorly of said frame, a hinged door or closure for the front side of the case supported in said frame, and latch means for said door housed within one of said compartments.
10. A case having a body consisting of a sheet metal plate forming the rear side of the case and having inwardly directed end portions to form the opposite ends and front side of the case and longitudinally extending flanges forming the opposite lateral edges of the case body, a frame secured within the case and having end walls cooperating with the ends of the body plate of the case to provide end compartments exteriorly of said frame, a hinged door or closure for the front side of the case supported in said frame, latch means for said door housed within one of said compartments, and means for removably retaining an article in the other of said compartments.
11. A case having a body consisting of a sheet metal plate forming the rear side of the case and having inwardly directed end portions to form the opposite ends and front side of the case and longitudinally extending flanges forming the opposite lateral edges of the case body, a frame having end walls cooperating with the ends of the body plate of the case to provide end compartments exteriorly of said frame, means for detachably securing said frame within the case, a hinged door or closure for the front side of the case supported in said frame, latch means for said door housed within one of said compartments.

ments, means for removably retaining an article in the other of said compartments, a sheet of ornamental flexible material covering the outer surfaces of the body plate of the case, and said frame having parts engaging the ends of said covering sheet to removably secure the same upon the case body.

12. A vanity case having a body consisting of a sheet metal plate forming the rear side of the case and having inwardly directed end portions forming the opposite ends and front side of the case body, a frame secured within the case and having an end wall cooperating with one end of the body plate of the case to form an end compartment exteriorly of said frame, said body plate having longitudinally extending flanges forming the opposite lateral edges of the case body and closing the opposite ends of said compartment, one of said flanges having an opening through which a lipstick may be inserted into or withdrawn from said end compartment, and closure means for the open front side of the case mounted in said frame.

13. A vanity case having a body consisting of a sheet metal plate forming the rear side of the case and having inwardly directed end portions forming the opposite ends and front side of the case body, a frame secured within the case and having an end wall cooperating with one end of the body plate of the case to form an end compartment exteriorly of said frame, said body plate having longitudinally extending flanges forming the opposite lateral edges of the case body and closing the opposite ends of said compartment, guide means in said compartment for a lipstick holder movable through said opening, and closure means for the open front side of the case mounted in said frame.

14. A vanity case having a body consisting of a sheet metal plate forming the rear side of the case and having inwardly directed end portions forming the opposite ends and front side of the case body, a frame detachably secured to said body plate within the case and having end walls cooperating with the ends of said body plate to form end compartments exteriorly of said frame, a closure for the open front side of the case between the ends of the body plate hingedly supported in said frame, means carried by the frame to removably retain cosmetic holding trays therein, said body plate having longitudinally extending flanges forming the opposite lateral edges of the case body and closing the ends of said compartments, latch means for said hinged closure housed in one of said end compartments, and means for removably retaining a lipstick holder in the other of said end compartments.

15. A vanity case having a body consisting of a sheet metal plate forming the rear side of the case and having inwardly directed end portions forming the opposite ends and

front side of the case body, a frame detachably secured to said body plate within the case and having end walls cooperating with the ends of said body plate to form end compartments exteriorly of said frame, a closure 70 for the open front side of the case between the ends of the body plate hingedly supported in said frame, means carried by the frame to removably retain cosmetic holding trays therein, said body plate having longitudinally extending flanges forming the opposite lateral edges of the case body and closing the ends of said compartments, latch 75 means for said hinged closure housed in one of said end compartments, said latch means including a part overlying a wall of one of the cosmetic holding trays when the closure is open to prevent displacement of the tray relative to said frame, and means for removably retaining a lipstick holder in the 80 other of said end compartments.

16. A vanity case having an outline contour simulating a miniature kodak camera, said case consisting of an elongated sheet metal plate forming the rear side of the case and having its opposite end portions inwardly turned and spaced from said rear side of the case to form the opposite ends and front wall sections of the case, a door hingedly supported in the case to close the space between said front wall sections thereof, and ornamental metal edge plates secured to said body plate of the case and each having a continuous marginal flange extending inwardly upon the rear side wall and the front 95 wall sections of the case body.

17. A vanity case having an outline contour simulating a miniature kodak camera, said case consisting of an elongated sheet metal plate forming the rear side of the case and having its opposite end portions inwardly turned and spaced from said rear side of the case to form the opposite ends and front wall sections of the case, a door hingedly supported in the case to close the space between said front wall sections thereof, ornamental metal edge plates secured to said body plate of the case and each having a continuous marginal flange extending inwardly upon the rear side wall and the front wall 100 sections of the case body, a sheet of flexible ornamental material covering the outer surfaces of said sheet metal body plate and held against lateral shifting movement relative thereto by the flanges on said edge plates, and means securing the ends of said flexible sheet of material upon the front wall sections of the case body at the opposite ends of the door receiving opening.

18. A vanity case having an outline contour simulating a miniature kodak camera, said case consisting of a body structure including an elongated sheet metal plate having an intermediate portion forming the rear side wall of the case and the opposite end por- 110 120 125 130

tions of said plate inwardly turned and extended in parallel relation to said intermediate portion to form spaced front wall sections, closure members for the opposite lateral edges of the case body secured to said plate and having parts cooperating with said front wall sections to retain the same in spaced relation to the rear wall of the case body, and a door hingedly supported in the case at the front side thereof to close the space between said front wall sections thereof.

In testimony that I claim the foregoing as my invention, I have signed my name hereto.

DAVID H. ZELL.
